Attorney, Agent, or Firm—Scott R. Foster

[57] CLAIM

The ornamental design for a razor handle, substantially as shown and described.

DESCRIPTION

FIG. 1 is a front elevational view of a razor handle showing my new design;

FIG. 2 is a right side elevational view thereof, the opposite side being substantially a mirror image thereof;

FIG. 3 is a rear elevational view thereof;

FIG. 4 is a top plan view thereof; and

FIG. 5 is a bottom plan view thereof.
